[57] CLAIM

The ornamental design for a clamp for a garment hanger, as shown and described.

DESCRIPTION

FIG. 1 is a front elevational view of a clamp for a garment hanger showing my new design, the rest of the hanger being shown in broken lines for illustrative purposes only;

FIG. 2 is a top plan view thereof;

FIG. 3 is a bottom plan view thereof;

FIG. 4 is an enlarged front perspective view thereof,
the rear being unornamented;

FIG. 5 is an enlarged left side elevational view thereof,
the right side being a mirror image.

Fig. 4.

Fig. 5.
